UNITED STATES PATENT OFFICE.

ETIENNE FAJON, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 15,164, dated July 29, 1984.

Application filed December 11, 1883. Term of patent 33 years.

To all whom it may concern:

Be it known that I, ETIENNE FAJON, of Boston, in the county of Suffolk and State of Massachusetts, have invented a new and original 5 Design for Carpets, of which the following is a specification.

The nature of my design is fully shown in the accompanying photographic illustration.

The design is composed of the finely mottled 10 or speckled groundwork visible at various points throughout the pattern, the fan-shaped and variously-formed angular figures thereon, and the floral and foliage ornamentation, all as shown.

15 I am aware of Design Patent No. 13,579 to W. J. Gadsby, and do not claim the design shown therein. My design differs from that shown in said patent, first, in the form of the figures and floral ornamentation, and, secondly,

in the mottled groundwork of uniform appearance visible at various parts of the pattern. This is not found in Gadsby's patent, the groundwork therein shown being variegated and presenting no uniformity throughout the pattern. The effect is therefore quite different from that of mine. 20 25

I claim—

The design for a carpet, as shown and described.

In testimony whereof I have signed my name 30 to this specification, in the presence of two subscribing witnesses, this 7th day of December, 1883.

ETIENNE FAJON.
